US0D1087491S

(12) **United States Design Patent** (10) **Patent No.:** **US D1,087,491 S**
(45) **Date of Patent:** **** Aug. 5, 2025**

(54) **PET FEEDER**

(71) Applicant: **Nenghua Liao**, Huizhou (CN)

(72) Inventor: **Nenghua Liao**, Huizhou (CN)

(**) Term: **15 Years**

(21) Appl. No.: **29/999,005**

(22) Filed: **Apr. 16, 2025**

(51) LOC (15) Cl. **30-07**

(52) U.S. Cl.

USPC **D30/122**

(58) **Field of Classification Search**
